UNITED STATES PATENT OFFICE.

BENJAMIN F. BARNES, OF ROCKFORD, ILLINOIS, ASSIGNOR TO THE B. F. BARNES COMPANY, OF SAME PLACE.

DESIGN FOR A FRAME FOR DRILLING-MACHINES.

SPECIFICATION forming part of Design No. 32,796, dated June 5, 1900.

Application filed May 8, 1900. Serial No. 15,983. Term of patent 7 years.

To all whom it may concern:

Be it known that I, BENJAMIN F. BARNES, a citizen of the United States, residing at Rockford, in the county of Winnebago and State 5 of Illinois, have invented and produced a new and original Design for Frames for Drilling-Machines, of which the following is a specification, reference being had to the accompanying drawings, forming part thereof.

10 Figure 1 is a perspective view of a frame for drilling-machines as seen from the front, showing my new design. Fig. 2 is a similar representation as seen from the rear.

15 As shown in the drawings, the leading or material features of my design consists of the column 1, a curved arm 2, supporting a head 3, a curved portion 4, supporting a bearing 5, a portion 6, and a brace 7, supporting a head 8 at the point of junction. An extension 9 20 supports a bearing 10. The lower portion 11 of the curved portion 4 blends into the lower portion of the curved arm 2. A rib projec-

tion 12 extends from the upper face of the curved arm 2. An opening 13 is formed in the head 3. An opening 14 extends through the head and a raised projection 15 extends horizontally below this opening. In the lower portion of the curved arm 2 is formed an opening 16, having an enlarged center portion 17.

25 Having described my invention, what I claim as new, and desire to secure by Letters Patent, is—

30 The design for a frame for drilling-machines substantially as herein shown and described.

35 In testimony whereof I have signed my name to this specification in the presence of two subscribing witnesses.

BENJAMIN F. BARNES.
